UNITED STATES PATENT OFFICE.

HARLEY M. DUNLAP, OF BATTLE CREEK, MICHIGAN.

PNEUMATIC TOOL.

No. 885,985.

Specification of Letters Patent.

Patented April 28, 1908.

Application filed April 18, 1904. Serial No. 203,724.

To all whom it may concern:

Be it known that I, HARLEY M. DUNLAP, a citizen of the United States, residing at the city of Battle Creek, in the county of Calhoun, State of Michigan, have invented certain new and useful Improvements in Pneumatic Tools, of which the following is a specification.

This invention relates to improvements in pneumatic tools.

My improved pneumatic tool is particularly adapted for use as a massaging device or hammer for giving massage treatments, although it is adapted for other uses such as pneumatic hammers and the like are generally applied to.

The objects of this invention are—First, to provide an improved pneumatic tool or hammer which is simple in structure and economical to produce and convenient economical and durable in use. Second, to produce an improved pneumatic tool adapted for use as a massage device or hammer for giving massage treatments adapted to produce a very rapid vibratory movement and one which is under the control of the operator.

Further objects and objects relating to structural details will definitely appear from the detailed description to follow.

I accomplish the objects of my invention by the devices and means described in the following specification.

The invention is clearly defined and pointed out in the claims.

A structure embodying the features of my invention is clearly illustrated in the accompanying drawing forming a part of this specification, in which,

Figure 1 is a central longitudinal sectional view through a structure embodying the features of my invention. Fig. 2 is a detail longitudinal sectional view of a modified structure showing a movable tool holder or socket.

Referring to the drawing, a cylinder A having heads A' A'' is provided. These heads are preferably screwthreaded onto the cylinder so that the parts are readily assembled. The head A'' is provided with a tool holder or socket a'' made integral therewith. Within the cylinder A is a piston or plunger B. The upper or outer portion of the piston B is provided with a central longitudinal chamber-like passage g opening at the outer end of the piston. The piston B is

also provided with an annular groove-like passage g'. This groove is connected to the longitudinal passage or chamber g by radial passages g''. The groove b' is adapted to register with the air inlet port d of the cylinder when the plunger is in its initial or outer position, and is cut off therefrom by the piston when it is in its inner position. The cylinder is provided with an exhaust port c located below the inlet port d. This exhaust port is adapted to open into the annular passage or groove g' when the piston is in its inner position.

The lower portion of the piston B is of reduced diameter to provide a shoulder against which the coiled spring a rests. This spring serves to return the piston to its initial position. Arranged in a suitable seat or socket in the head A'' of the cylinder, is a rebound spring a' which is adapted to receive the blow of the piston and to aid in returning it to its initial position. A vent port c' is provided for the lower portion of the cylinder. This vent allows the air in front of the piston to escape as the piston is forced inwardly.

Air is supplied to the port d through the hollow stem D of the handle F. The handle F is provided with a nipple G adapted to receive a suitable air supply pipe, as is indicated in dotted lines. I control the delivery of air to the cylinder by an inwardly opening valve E which is provided with a stem E' adapted to be actuated by the thumb of the user. The stem E' is arranged through a chamber e. Supported within this chamber is a diaphragm e', dividing the chamber into two parts, the lower portion being connected to the air supply, so that the valve is closed automatically, when it is released by the operator, by the air supply pressure. The valve stem E' passes through and is connected to this diaphragm.

In operation, air is admitted through the valve E, the same being opened inwardly by the pressure of the operator. The air entering the annular passage b' through the inlet port d, passes thence through the passages b'' and b into the cylinder. This drives the piston forward until the annular groove or passage B' registers with the exhaust ports c, which allows the cylinder to exhaust. As the annular passage b' is of considerable width the piston continues to take air while the piston is moving forward until the intake port is covered. The intake port and the exhaust port and the annular passage are so

arranged that the intake is cut off just as the exhaust port begins to open. By the impetus which the piston receives from the air and by the expansion of the air behind it, 5 the piston is driven inward against the action of the return spring until it strikes the rebound spring a' . As the cylinder is by this time exhausted, this throws the piston quickly back to the starting point. The 10 result is that a vibratory movement is imparted to the whole device. Thus arranged, the movement of the piston is very rapid.

I desire to remark that the rebound spring may be omitted and still very satisfactory 15 results be secured. It is, however, of advantage in that the return spring can then be of only sufficient strength to return the piston to its initial position. I further desire to remark that the return spring may be omitted 20 if desired, the rebound spring only being used. In this case, it is necessary, however, that the piston be jarred or otherwise forced to its initial position at the outer end of the cylinder in starting. The action of the 25 device is also less regular, its movement varying slightly according to the different positions in which the instrument is held. I preferably provide the return spring of just sufficient strength to return the piston to its 30 initial position against its own weight. The springs are very different from air confined by the piston because they are positive in their action, the parts need no fitting to confine the air and less friction is consequent and 35 less force expended.

In the modified structure shown in Fig. 2, a movable tool holder or socket F is provided. This tool holder F is reciprocatingly secured in the head A' by a thumb screw f 40 which engages a longitudinal groove therein. The inner end of the holder F is provided with a seat for the rebound spring a' . Thus arranged, the blows of the piston are delivered to the tool holder or socket.

45 In use, the rapidity of the vibration is controlled by the quantity of air admitted to the cylinder and the amount of pressure. The amount of air admitted can be easily controlled by the operator with the valve I have 50 shown. I am, however, aware that there are numerous styles of valve which would prove satisfactory.

I have illustrated and described my improved pneumatic tool in the form preferred 55 by me on account of its structural simplicity and economy, and its convenience in use. I am, however, aware that it is capable of considerable variation in structural details without departing from my invention.

60 Having thus described my invention, what I claim as new and desire to secure by Letters Patent, is:

65 1. In a structure of the class described, the combination of a cylinder; a piston having a longitudinal passage opening at its

outer end and an annular passage connected to said longitudinal passage; an inlet port for said cylinder adapted to register with said annular passage when said piston is in its initial or outer position, and to be closed by 70 said piston when the same is in its inner position; an exhaust port adapted to register with said annular passage when said piston is in its inner position; a vent port for the inner end of said cylinder; a return spring 75 adapted to engage the lower end of said piston; a rebound spring adapted to receive the blows of said piston; a laterally projecting handle for said cylinder, having a passage therethrough, connected to said inlet port; and an automatic valve adapted to control 80 said passage, arranged in said handle, for the purpose specified.

2. In a structure of the class described, 85 the combination of a cylinder; a piston having a longitudinal passage opening at its outer end and an annular passage connected to said longitudinal passage; an inlet port for said cylinder adapted to register with said annular passage when said piston is in its initial or outer position, and to be closed by 90 said piston when the same is in its inner position; an exhaust port adapted to register with said annular passage when said piston is in its inner position; a vent port for the inner end of said cylinder; a return spring 95 adapted to engage the lower end of said piston; and a rebound spring adapted to receive the blows of said piston, for the purpose specified.

3. In a structure of the class described, 100 the combination of a cylinder; a piston having a longitudinal passage opening at its outer end and an annular passage connected to said longitudinal passage; an inlet port for said cylinder adapted to register with said annular passage when said piston is in its initial or outer position, and to be closed by 105 said piston when the same is in its inner position; an exhaust port adapted to register with said annular passage when said piston is in its inner position; a vent port for the inner end of said cylinder; a return spring 110 adapted to engage the lower end of said piston; a laterally projecting handle for said cylinder, having a passage therethrough, connected to said inlet port; and an automatic valve adapted to control 115 said passage, arranged in said handle, for the purpose specified.

4. In a structure of the class described, 120 the combination of a cylinder; a piston having a longitudinal passage opening at its outer end, and an annular passage connected to said longitudinal passage; an inlet port for said cylinder adapted to register with said annular passage when said piston is in its initial or outer position, and to be closed by 125 said piston when the same is in its inner position; an exhaust port adapted to register 130

- with said annular passage when said piston is in its inner position; a vent port for the inner end of said cylinder; a rebound spring adapted to receive the blows of said piston; 5 a laterally projecting handle for said cylinder, having a passage therethrough, connected to said inlet port; and an automatic valve adapted to control said passage, arranged in said handle, for the purpose specified.
- 10 5. In a structure of the class described, the combination of a cylinder; a piston having a longitudinal passage opening at its outer end, and an annular passage connected to said longitudinal passage; an inlet port for said cylinder adapted to register with said annular passage when said piston is in its initial or outer position, and to be closed by said piston when the same is in its inner position; an exhaust port adapted to register with said annular passage when said piston is in its inner position; a return spring adapted to engage the lower end of said piston; a rebound spring adapted to receive the blows of said piston; and an automatic valve 15 adapted to control said inlet port, for the purpose specified.
- 20 6. In a structure of the class described, the combination of a cylinder; a piston having a longitudinal passage opening at its outer end, and an annular passage connected to said longitudinal passage; an inlet port for said 25
- 25 cylinder adapted to register with said annular passage when said piston is in its initial or outer position, and to be closed by said piston when the same is in its inner position; an exhaust port adapted to register with said annular passage when said piston is in its inner position; a movable tool holder or socket and a rebound spring for said piston, for the purpose specified. 55
- 30

cylinder adapted to register with said annular passage when said piston is in its initial or outer position, and to be closed by said piston when the same is in its inner position; 35 an exhaust port adapted to register with said annular passage when said piston is in its inner position; a return spring adapted to engage the lower end of said piston; and a rebound spring adapted to receive the blows 40 of said piston, for the purpose specified.

7. In a structure of the class described, the combination of a cylinder; a piston having a longitudinal passage opening at its outer end and an annular passage connected to said 45 longitudinal passage; an inlet port for said cylinder adapted to register with said annular passage when said piston is in its initial or outer position, and to be closed by said piston when the same is in its inner position; 50 an exhaust port adapted to register with said annular passage when said piston is in its inner position; a movable tool holder or socket and a rebound spring for said piston, for the purpose specified.

In witness whereof, I have hereunto set my hand in the presence of two witnesses.

HARLEY M. DUNLAP.
